UNITED STATES PATENT OFFICE.

JOHN GARDNER, OF NEW HAVEN, CONNECTICUT, ASSIGNOR TO THE WINCHESTER REPEATING ARMS COMPANY, OF SAME PLACE.

PUNCHING AND DRAWING PRESS.

SPECIFICATION forming part of Letters Patent No. 271,831, dated February 6, 1883.

Application filed August 28, 1882. (No model.)

To all whom it may concern:

Be it known that I, JOHN GARDNER, of New Haven, in the county of New Haven and State of Connecticut, have invented new Improvements in Punching and Drawing Presses; and I do hereby declare the following, when taken in connection with accompanying drawings and the letters of reference marked thereon, to be a full, clear, and exact description of the same, and which said drawings constitute part of this specification, and represent, in—

Figure 1, a front view, and Fig. 2 a side view, of a press embodying my invention; Fig. 3, an upper side view of the cross-head which carries the cutting-punch, enlarged; Fig. 4, a vertical central section through the punches and die, enlarged; Fig. 5, the disk cut by the punch; Fig. 6, the cup.

This invention relates to an improvement in double-action presses, such as used for the operation of what is commonly called "cupping"—that is to say, in which one punch enters a die to cut a disk from the sheet placed therein, while a smaller punch working concentrically through the cutting-punch forces the disk cut by the first punch down through a die of smaller diameter, so as to draw the disk into a cup shape, Fig. 5 representing the disk as cut from the sheet, and Fig. 6 a vertical section of the cup drawn from the disk. The cups are used for various purposes. My invention, however, is intended more especially for drawing cups for the manufacture of cartridge-shells, but is equally applicable for other purposes. In this class of presses two independent slides are employed, the one carrying a hollow cutting-punch, the other the internal drawing-punch, and arranged so that the first head operates in advance of the second, and so that the disk is first cut. The second head then advancing, the internal punch performs the drawing operation. This is a class of presses too well known to require particular description. In cutting the disks from the sheet it is necessary that the cuts shall be made in the closest possible proximity to each other, so as to avoid waste. Dies and punches have been arranged in series or clusters, so as to cut entirely across the strip; but in such

machines great difficulty has been experienced in adjusting the dies and punches relatively to each other. To obviate these difficulties is the object of my invention; and it consists in the arrangement of the parts for independent adjustment each of another, as more fully herein-after described. 55

A represents the die-block; B, the cross-head carrying the cutting-punches, and C the cross-head carrying the drawing-punches, each operated independently by the driving-shaft, 60 and timed relatively to each other in the usual manner, too well known to require particular description.

In the die-block the dies *a* are arranged in two series corresponding to the two transverse 65 lines of cuts to be made, the cuts indicated by the larger diameters in Fig. 3, those in one series standing in line between those of the next series, so that the cuts are made in the usual manner of punching and with the least 70 possible waste of metal.

Above the die is a plate, *b*, between which and the dies the sheet *D* passes, as seen in Fig. 4, in the usual manner, the plate *b* serving to hold the sheet down upon the die, and 75 so as to prevent the plate from lifting with the punch. These dies may be arranged and secured in the usual manner. Their upper internal diameter corresponds to the size of the disk to be made, the portion below to the diameter 80 of the drawn cup.

The cross-head *B* has vertical perforations *d* through it, corresponding substantially to the several dies below. Into these perforations or openings *d* the several cutting-dies *e* are 85 arranged.

The dies *e* are constructed with their working end corresponding to the diameter of the die and of the disk to be cut. They are provided with a shoulder, *f*, to rest and take a 90 bearing against the under side of the cross-head *B*. The body *h* of the die is of somewhat less diameter than the opening *d* in the cross-head, as seen in Fig. 4. The upper end of the body is threaded, and onto this threaded 95 end a nut, *i*, is turned to a hard bearing upon the upper side of the cross-head. This nut above and shoulder below clamp the punch firmly to the cross-head, and because the body of the punch is of less diameter than the opening 100

through the cross-head the punch may be adjusted relatively to the die below by simply loosening the nut *i*, properly setting the punch, and then returning the clamping-nut *i*.

5 The dies being properly adjusted, the punches free or unclamped in their seats in the cross-head, the cross-head is brought down until the punches properly enter and stand in the dies. Then, when so entered, the clamping-nuts are 10 screwed down, thereby securing the punches in their proper relative position to the dies, each punch having its own independent adjustment, and, when adjusted, secured by clamping in a diametrical line, prevents the 15 cramping of the punches in the dies, so as to cause them to bind or improperly work therein, as is unavoidably the case in the usual diametrical or radial clamping adjustment.

The second cross-head C, carries a holder, E, 20 into which freely slides a flat plate, F. This holder is arranged directly over the punches in the head below. The plate F has perforations or openings *l* corresponding to the punches below. Into the openings or seats *l* in the 25 plate the drawing-punches L are arranged. These punches correspond to the internal diameter of the cup to be drawn, and the cutting-punches e are hollow, the opening through them corresponding to the drawing-punches, 30 as seen in Fig. 4, and so that the drawing-punch will play freely therein up and down. Each punch is independently held in the plate, preferably by making an annular groove, *m*, in the upper end of the punches, and then introducing a transverse follower, *n*, into the 35 edge of the plate to engage said groove, as seen in Fig. 4, and so that the end of the punches may stand against the under surface of the holder E.

40 The opening in the plate for the punches L is made larger in diameter than that end of the punches, so as to allow play therein, substantially as do the openings through the head, and so that in adjusting the punches in the 45 plate below the drawing-punches will readily move in their own holder to adapt themselves to the punch below—that is to say, they yield readily to permit the adjustment of the punch below and adapt themselves to such movement.

If at any time it is desirable to remove either of the punches L without disturbing the punch below, it is done by simply withdrawing the follower *n* from connection with the 55 punch; then it will drop down through the punch and die below, and may be replaced by reversing the operation; or if at any time it is desirable to remove one or more of the drawing-punches for examination or repairs, it is 60 only necessary to remove the head B. The plate F, being free, will pass out with it. Then the punches may be examined, repaired, or whatever it may be necessary to do to them. They

may then be returned to their place with the head, and in such removal they have not been 65 disturbed in their relative position to the die, and do not require readjustment, as in the usual construction of such presses.

The adjustment of the punches *e* may be employed in single-action presses where only a 70 cutting out of the disk is required, and all the advantages of such adjustment will be attained in such a press.

The sliding plate F, carrying the drawing-punches, each free for self-adjustment relative 75 to the punches below, may be employed in presses in which the cutting-punch is fixed in its head without adjustment. In such construction the advantages of the self-adjustment of the drawing-punch relative to the cutting-punch will be attained.

The dies *a* are constructed with a shoulder, *r*, to take a bearing on a corresponding seat against the thrust of the punching operation. The body extends downward through an opening in the die-holder of larger diameter than the body itself, and so as to permit radial movement of the die, with a nut or other clamping device, *s*, below, which will clamp and secure the die in place, so that the die may also be 90 adjusted with relation to the punch. In some cases it may be more convenient to adjust the die than the punch, and vice versa. Therefore I prefer to make both the punch and dies adjustable relatively to each other, also the 95 punches to themselves and the dies to themselves, and as seen in Fig. 4.

I claim—

1. In a punching-press, a hollow cutting-punch constructed with a body of less diameter than its seat in the cross-head, and with a shoulder to take a bearing against the downward force of the cross-head, and with a clamping device upon the opposite end of the punch to permit the adjustment of the punch in the 105 cross-head, with a drawing-punch operated independently through the cutting-punch, and hung in a seat in the second cross-head, above said seat, of larger diameter than the drawing-punch, whereby the radial adjustment of the 110 cutting-punch will be correspondingly imparted to the drawing-punch, and mechanism, substantially such as described, to impart a reciprocating movement to said cross-heads and punches, substantially as described. 115

2. The combination, with the cross-head B, of the cutting-punches, the cross-head C, the sliding plate F, arranged therein, the drawing-punches, and mechanism, substantially such as described, to impart a reciprocating movement 120 to said cross-heads and punches, substantially as described.

JOHN GARDNER.
